UNITED STATES PATENT OFFICE.

BENJAMIN F. BROOKE SEWELL, OF WASHINGTON, DISTRICT OF COLUMBIA.

APPARATUS FOR GENERATING GAS.

Application filed June 26, 1920. Serial No. 391,891.

My invention relates to the generation of gas from liquid fuel, such as fuel oil, (crude oil, crude oil residuum, tar, pitch, asphalt, or the like), or a combination of liquid fuel and water; or liquid fuel and steam; or liquid fuel, water and steam, and one object of my invention is to provide improved apparatus in which my improved method or process of generating gas can be carried out continuously and automatically; merely requiring priming of the generator by suitable inflammable material for the commencement of the operation, with a continuance of gas generation from heat evolved by burning a portion of the gas or vapor generated. The generator may be connected with the exhaust of an internal combustion engine which employs as its fuel the gas or gaseous vapor generated by the operation of my improved process, and this connection may be sufficient to render unnecessary the employment of any inflammable material as a priming agent.

A further and important object of my invention is to provide improved means for generating a gas or gaseous vapor from oil or equivalent liquid fuel; or oil and water; or oil and steam or oil, water and steam, which shall be available for use in internal combustion engines.

A further object of my invention is to provide means in the form of a generator that will be sufficiently flexible and automatic in its action in generating such gas or gaseous vapor as to be adapted for direct connection and combination with the engines of automobiles, and other motor-driven vehicles such as tractors, road engines, locomotives, or the like, also for motor-driven vessels, especially those of medium or small size.

A further object of my invention is to provide an improved method or process, and apparatus for carrying out the same, particularly available for household use, on farms, in manufacturing establishments, or the like, as well as for municipal gas plants of large or small capacity.

A still further object of my invention is to provide apparatus which may be arranged for manual control, fully or partially, that is, semi-automatic, or it may be completely automatic in its action; the controlling mechanism being readily adjusted

for operation under these several conditions.

As may be well understood, apparatus within the scope of my invention is capable of many practical modifications all, or most of which, however, have the following parts or their equivalent for the desired purpose in common, to wit:

Means including suitable connections for delivering liquid fuel from convenient sources to one or more heated and preferably closed spaces, (for instance, retorts, pipes, tubes, worms, or the like), in which such liquid fuel is heated sufficiently to form the desired gas or gaseous vapor; suitable valves for controlling the delivery and rate of flow of such liquid fuel; means whereby air may be excluded from the enclosed heating spaces during the time gas is being made therein; one or more burners which may utilize a portion of the gas or gaseous vapor generated or other suitable fuel to heat the enclosed heating spaces; a suitable condensing or cleaning system to condense and permit removal from the gas of any vapor, liquid, or foreign matter mixed or entrained therewith, and means to automatically control the temperature of the heating chamber in accordance with the amount of liquid fuel that is being fed for gas generating purposes.

Other parts or elements desirable for the proper operation of apparatus within the scope of my invention, and which may be employed in carrying out my improved process, may include means for automatically utilizing the thermo-dynamic conditions, (that is, pressure, volume, and temperature) of the gas generated to govern the operation of the apparatus employed and to make it wholly automatic. In other words, the thermo-dynamic condition of the gas is used (either directly or indirectly) to govern and regulate the various parts of the operating elements surrounding the enclosed heating spaces, and the like, and to insure that a sufficient but not excessive amount of gas is efficiently produced by the apparatus; the quantity produced automatically being determined in proportion to or in relative accordance with the amount required for use.

The various forms of apparatus which I have devised for carrying out my improved

method or process provide self-contained, self-governing, automatic machines for making gas from liquid fuel, and their arrangement and method or manner of operation 5 distinguish them from all other apparatus having in view a similar purpose.

Apparatus constructed in accordance with my invention is primarily intended for the generation of a gas which may be employed 10 as an illuminating or heating medium, or as fuel for engines of the explosive type, but it will be understood that it may be advantageously employed for refining oil and for the production of various oil products.

15 These and other features of my invention are more fully described hereinafter, reference being had to the accompanying drawings, in which I have illustrated, somewhat diagrammatically, various forms of self-contained and self-governing apparatus within the scope of my invention, and it will be noted that the several forms of apparatus 20 include certain basic features, all more fully pointed out hereinafter.

In the drawings:

Figure 1, is a side elevation, partly in section and more or less diagrammatic in character, of a complete, self-contained and self-governing gas-generating apparatus within the scope of my invention.

Figs. 2 and 3, are similar views illustrating other forms of apparatus capable of performing the same functions in a slightly different manner.

35 Figs. 4 and 5, are enlarged fragmentary views in elevation of portions of the structure shown in Fig. 1, and Fig. 6, is an enlarged view of a portion of the structure shown in Fig. 2.

40 The gas generating apparatus shown in Fig. 1, of the drawings includes, among other elements, a suitable tank for liquid fuel, a fuel feeding device, a vaporizer, a gasifier, automatically actuated regulating 45 mechanism for controlling the operation of the apparatus, and a heating system, all as more fully described hereinafter.

While this apparatus is shown as provided with automatic regulating means, it 50 will be understood that it, as well as the various other forms of my improved gas generating apparatus, is also designed for manual control, and it may be placed in condition for automatic control or manual control by connecting or disconnecting certain 55 elements of the apparatus without in any way affecting the operation of generating the gas or gaseous vapor, so long as liquid fuel is fed to the heating chamber. In this 60 form of my improved apparatus, there is no admixture of water with the liquid fuel, although it will be understood that I may make provision for the introduction of water with the liquid fuel without departing from 65 my invention. In designing this form of

apparatus I have endeavored to provide means giving a high degree of thermal efficiency at low loads.

The relative position of the various parts of the apparatus shown in Fig. 1, is that assumed when the apparatus is generating gas at full capacity. In this view, 1 designates a reservoir or tank for liquid fuel, and such liquid fuel may be fuel oil, crude oil, crude oil residuum, tar, pitch, asphalt, or the like, as above described.

70 The tank 1, having been filled with liquid fuel may be raised by hand-crank 2 and cables 3 and 4, to the position shown in the drawing and feeds liquid fuel through flexible tube 5, past governed valve 6, adjusting valve 7 and sight feed 8, into an inner pipe 9, which extends into and passes through part of the retort or pipe 10; the lower part 75 of which pipe 10 is heated in the manner hereinafter described. This inner pipe 9, is heated by the hot ascending gases passing upwardly through the retort, and the cool liquid fuel passing down through this inner pipe 9, is thereby heated progressively; the recuperative effect economizing fuel as well 80 as cooling the gas. The liquid fuel is more or less vaporized, depending on the character of fuel used and the temperatures to which the same is subjected, and there may even be some gas formed in this pipe 9.

85 The portion of the liquid fuel that is not gasified may pass from trough 13 through cross connection 14 at the end of pipe 10, pipe 15, and valve 16 to a tar receptacle 16^a, having inlet and outlet passages 17 and 18, controlled by valves 19, 19^a and 19^b, suitably connected together for simultaneous operation so that when the inlet is open the outlet 90 will be closed, and vice versa. The vapors issuing from the lower end of pipe 9, are heated by or from the hot walls of pipe or retort 10, and through this heating permanent gas is formed. By "permanent" gas I 95 mean gas which is not condensed as liquid at ordinary, habitable, room temperatures.

100 The highly heated gas formed from the liquid fuel, which may be mixed with or may contain some vapors, (by vapors I mean gases which will liquefy or form the opaque particles of a fog at ordinary room temperature), flows in an upward direction outside pipe 9, and inside pipe 10; that is to say, 105 this highly heated gas flows between these two pipes to the storage chamber. As stated above, the incoming liquid flows downwardly inside the inner pipe 9, and the hot gas passing upwardly through pipe 10, around pipe 9, is thereby cooled. Through 110 this recuperative effect there is a saving in the amount of fuel needed to heat the retort, and that part of the apparatus used solely for cooling the gas may be made smaller.

115 From retort or pipe 10, the gas passes 120 through tee 20, and valve 21, into cooling

pipes 22 and 23. Any suitable arrangement of cooling pipes may be employed for this purpose. The cooled gas passes from pipe 22, through pipe 24, valve 25, tee 26, pipe 27, into gas tank 28; such gas tank being shown as being filled, with the bell 30, in the act of rising. The parts of the apparatus that automatically govern its operation, and which are actuated by the gas bell 30, will be described later.

The gas passes out of gas tank 28, through pipe 31, cross connection 32, valve 33, sawdust purifier 34, valve 35, and through regulating or reducing valve 36 which regulates the pressure of the gas, so that the delivery pressure always remains substantially the same. The gas that is to be used for external consumption moves past branch connections (that lead to the burners and are later described) and through L-connections 37 and 38, pipes 39 and 40, valve 41, tee 42, and out to the point of consumption.

Gas for the pilot burner 45 branches off from tee 46 and passes through valve 47 and pipe 48 to said burner. A sufficient amount of gas is always supplied to the pilot burner so that when the main burner supply is turned off, (the liquid fuel feed also being cut off), this pilot burner will remain burning. Later, as will be described in connection with the governing mechanism, a burner 49 may be turned on, and this burner 49 is large enough to raise and maintain the temperature of the retort at the desired point in order that gas generation can be resumed at any time. The pilot burner 45 is of minimum size in order to economize in consumption of gas when little or none is required for outside use.

Gas for a main burner 50, which is in action when the apparatus is generating gas, is branched off through tee 51, and passes through governed valve 52, pipe 53, valve 54, to the burner. The governed valve 52, in the position shown, is open for the passage of gas to the main burner 50, since the parts of the apparatus are shown in the relative position they assume just after the commencement of the gas generating period. The hot combustion gases from the burner 50 pass into chamber 55, surrounding the hottest part of the retort and travel upward through spaces 56 and 57, and out through smoke-stack 58.

As stated, with the parts of the machine in the relative position shown, the valve 52 controlling the main burner 50, and the valve 6 controlling the liquid fuel feed have just been turned on. These valves may be turned on by suitable means actuated by the descending bell of the gas tank as follows:

When the bell reaches the position shown, a lug 60 has just engaged roller 61, so as to depress levers 62 and 63, and the depre-

sion of these levers causes a weight 64 to throw "over centre" that is to say, to overbalance, pulling link 65, and buffer 66 against stop 67. By means of a connection 68, an angular motion is imparted to a bell-crank lever 69, which raises rod 70 and this action opens valve 6, in the liquid fuel line, and simultaneously, by means of rod 71, valve 52 in the gas line is opened. The raising of rod 71, moves an offset latch 72 which may be employed to engage a lever 72^a and close a valve 72^b in a pipe line 73, leading from a tee 74, to the burner 49, and additionally it moves a bell crank 75. The angular motion imparted to bell-crank 75, as shown, moves a rod 76 so as to open a damper 77 in stack 58. When the damper is closed, only enough air is pulled in by the draft to support combustion of the gas burnt by the burner 49.

The apparatus, as shown, is operating at full capacity. A little while before the gas bell 30 has reached its upper limit of travel, the lug 60 has engaged a roller 80, and raises it so that weight 64 is thrown "over centre" again; but this time it is thrown over in a direction opposite to that set forth above. This time link 65 together with a buffer 81, are pushed against stop 82, and the rod 70 is depressed. This causes the governed valves 6 and 52, to close, and the damper 77 to be almost closed. The apparatus now is shut down, except for the pilot burner 45, which is still lit.

If at this time there should be little or no consumption of gas, then the bell 30 would practically remain full of gas; the only thermal loss being the amount of gas supplied to pilot burner 45, which is of minimum size and practically negligible. After the apparatus has been shut down for a while with the regulators in this position; the consumption of gas, however, continuing, the bell will have fallen again. But some time before the bell reaches the position where the lug 60 engages roller 61, a lug 600 on the opposite side of the bell has engaged a catch 601, pivoted at 602 to a lever 603 pivoted at 604, and said lever 603 is thrown outward; pulling chain 605, which opens valve 72^b in pipe line 73, so that gas may be supplied to burner 49. This burner 49 is sufficiently large to warm up the retort before the bell reaches the position to operate the necessary connections whereby the liquid fuel feed and supply of gas to the main burner 50, are turned on. The pipe 73 also contains a stop valve 73^a.

The handle 608 of the lever carrying the weight 64 may be used to operate the governing mechanism by hand; valve 72^b, in pipe line 73, of course, also being opened by hand in accordance with the requirements of hand operation.

When fixing or adjusting the sawdust

purifier, gas tank and governing parts of the machine, gas may continue to be supplied directly from the retort. Under such conditions valves 35, and 41, are closed, and a valve 85, in the inlet pipe 27 is also closed. After this, a valve 86 in the pipe 24, beyond the tee 26, is opened, and the gas may be by-passed through said valve 86, tee 42, and a pipe 87, for consumption.

10 Any tar or other impurities which may be entrained with the gas passing to pipe 24, may be drawn off through pipe 88, to a tar receptacle 166, having inlet and outlet passages 177 and 188, respectively, controlled by valves 199, 199^a and 199^b, suitably connected together for simultaneous operation so that when the inlet is open the outlet will be closed, and vice versa. Provision is also made for easily (and with minimum loss of time) burning off any carbon deposit that may adhere to the inside of pipes 9 or 10. The valve 21 is closed, and valves 16, 83 and 84, may be opened sufficiently for this purpose. Any tar accumulating in the sawdust purifier may be removed through a goose-neck trap 88^a, whose outlet 89 is controlled by a valve 89^a.

The apparatus shown in Fig. 2, is quite similar in construction and mode of operation to that shown in Fig. 1, except that it is simplified by the omission of the extra burner required for the greater low load thermal efficiency that is possible with apparatus of the character illustrated in Fig. 1. It also involves certain other details which will be more particularly pointed out hereinafter. The relative position of the various parts of the apparatus shown in Fig. 2, is that assumed when the machine is generating gas at full capacity. In this view, 1 and 1^a, designate, respectively, reservoirs for liquid fuel and water, and as above described, such liquid fuel may be fuel oil, crude oil, crude oil residuum, tar, pitch, asphalt, and the like.

The tank 1, (having been previously filled with liquid fuel and raised by a hand-crank 2^a and cables 3^a and 4^a, to the position shown), feeds liquid fuel through flexible tube 5^a, past governed valve 6^a, adjustment valve 7^a, sight feed 8^a, into the inner pipe 9^a, which extends into and passes through part of the retort or pipe 10^a; the lower part of said latter pipe being heated in the manner hereinafter described. This inner pipe 9^a is heated by the hot ascending gases in the retort, and the cool liquid fuel passing down through this inner pipe is thereby heated progressively; the recuperative effect economizing fuel as well as cooling the gas.

From tank 1^a warmed water passes down through pipe 11^a, past governed valve 12^a, and past other valves similar to those in the liquid fuel line and into the inner pipe 9^a;

the water and liquid fuel, flowing through this pipe together. These liquids are more or less vaporized, depending on the liquid fuel and the temperatures to which the combined liquids are subjected, and there may even be some gas formed in this pipe 9^a.

The portion of the liquid that is not vaporized or gasified is carried off by gutter 13^a, and may escape through connection 14^a at the end of the pipe 10^a, into pipe 15^a, and passing the governed valve 16^b enters the trough 17^a, where it may be brought into contact with air for the purpose of being burnt and furnishing part of the heat used to gasify the liquid fuel. Any excess may run off through overflow 18^a and away from the machine through a suitable pipe, such as indicated at 19^a.

The vapors issuing from the lower end of pipe 9^a, are heated by or from the hot walls of pipe or retort 10^a, and through this heating permanent gas is formed.

The highly heated gas formed from the liquid fuel, which may be mixed with or may contain some vapors, flows in an upwardly direction outside pipe 9^a and inside pipe 10^a, that is to say, this highly heated gas flows between these two pipes to the storage chamber. As stated above, the incoming liquid flows downwardly inside the inner pipe 9^a, and the hot gas passing upwardly through pipe 10^a around pipe 9^a is thereby cooled. Through this recuperative effect there is a saving in amount of fuel needed to heat the retort, and the part of the machine used solely for cooling the gas may be made smaller.

From retort or pipe 10^a, the gas passes through tee 20^a and valve 21^a, into cooling pipes 22^a and 23^a. Any suitable arrangement of cooling pipes may be used for this purpose. The cooled gas passes from pipe 22^a, through pipe 24^a, valve 25^a, tee 26^a, pipe 27^a, into gas tank 28^a. This gas tank is shown as being filled and the bell 30^a is in the act of rising. The parts of the machine that automatically govern its operation, and which are actuated by the gas bell 30^a, will be described later.

The gas passes out of gas tank 28^a, through pipe 31^a, cross connection 32^a, valve 33^a, sawdust purifier 34^a, valve 35^a, and through regulating or reducing valve 36^a, which regulates the pressure of the gas, so that the delivery pressure always remains substantially the same. The gas that is to be used for external consumption moves past branch connections (that lead to the burners) and through L-connections 37^a and 38^a, pipes 39^a and 40^a, valve 41^a tee 42^a, and out to the point of consumption.

Gas for the pilot burner 45^a branches off from tee 46^a, and passes through valve 47^a and pipe 48^a to said burner. A sufficient amount of gas is always supplied to the pilot

burner so that when the main burner supply is turned off (the liquid fuel feed also being cut off), this pilot burner will maintain the temperature of retort 10^a, in order that 5 gas generation can be resumed at any time.

Gas for the main burner 50^a which is used when the machine is generating gas, is branched off through tee 51^a and passes through governed valve 52^a, pipe 53^a, valve 10 54^a, to the burner. The governed valve 52^a in the position shown, allows gas to pass to the main burner 50^a since the parts of the apparatus are shown in the relative position they assume just after the commencement of 15 the gas generating period. These burners, together with the liquid fuel residue burnt in the trough 17^a furnish the hot combustion gases that heat the retort 10^a. These gases pass into chambered space 55^a surrounding the hottest part of the retort and travel upward through spaces 56^a and 57^a 20 and out through the smoke stack 58^a.

As stated, with the parts of the machine in the relative position shown, the main 25 burner 50^a and the liquid fuel feed have just been turned on. They are turned on by suitable means actuated by the descending bell 30^a of the gas tank, as follows:

When the bell reaches the position shown, 30 a lug 60^a has just engaged roller 61^a, so as to depress levers 62^a, and 63^a and the depression of these levers causes a weight 64^a to throw "over centre," that is to say, to overbalance; pulling link 65^a, and buffer 66^a, 35 against stop 67^a. By means of a connection 68^a, an angular motion is imparted to a bell-crank lever 69^a which raises a rod 70^a, and this action opens valve 6^a, in the liquid fuel line, and valve 12^a in the water line. 40 Simultaneously, by means of a rod 71^a, valve 52^a in the gas line is opened. The raising of rod 71^a moves a bell-crank lever 78^a which may be employed to actuate a bell-crank lever 79^a through a rod 74^a, and operate the 45 valve 16^b. The angular motion imparted to bell-crank lever 79^a, as shown, moves a rod 76^a so as to open a damper 77^a in stack 58^a. When this damper is closed, only enough air is pulled in by the draft to support combustion 50 of the gas burnt by the pilot burner 45^a.

The apparatus is shown in the position assumed when operating at full capacity. The gas tank, as indicated by the position 55 of the bell, still has considerable reserve capacity; so much so, that if more gas is required than can be made in the retort, then the machine is in position to deliver such peak demand for a short while, due to this 60 reserve capacity of its gas tank.

But normally, when the apparatus is producing, its production is greater than the demand, and the bell rises. A little while before the gas bell 30^a, has reached its upper 65 limit of travel, the lug 60^a has engaged

roller 80^a and raised it so that weight 64^a is again thrown "over centre"; but this time it is thrown over in a direction opposite to that set forth above. This time link 65^a, together with buffer 81^a, are pushed against 70 stop 82^a, and the rod 70^a is depressed. This causes the valves 6^a, 12^a and 52^a to close, and the damper 77^a to be almost closed. The apparatus is now shut down except for the pilot burner 45^a, which keeps the retort 75 sufficiently hot so that the gas making can be resumed whenever this should be required; that is to say, when the gas tank again reaches its lower limit of regular travel. 80

Provision is made for easily (and with a minimum loss of time) burning off any carbon deposit that may adhere to the inside of pipes 9^a and 10^a. The valve 21^a is closed, and valves 16^b, 83^a and 84^a may be opened 85 sufficiently for this purpose.

When fixing or adjusting the sawdust purifier, gas tank and governing parts of the machine, gas may continue to be supplied directly from the retort. Under this condition, valves 35^a and 41^a, are closed, and a valve 85^a, in the inlet pipe 27^a is also closed. After this, a valve 86^a in the pipe 24^a, beyond the tee 26^a, is opened, and the gas may be by-passed through said valve 86^a, tee 42^a, 90 and a pipe 87^a for consumption.

In Fig. 2, four pipes are shown in cross-section; three of which are for the purpose of carrying away from the immediate vicinity of the generator any tar that may be formed. Pipe 19^a has already been referred to and its function described; pipe 90 is for the purpose of carrying off any tar, which for any reason may inadvertently run into the fire-box; such pipe being provided with a funnel 90^a whereby any discharge from the fire-box may be directed thereto, and pipe 91 is to carry off any liquids that may condense in the part of the apparatus in which vapors carried with the gas are condensed 100 to liquid when the gas is cooled. Pipe 92 is employed to carry warm water to the household using the apparatus. 105

Water is warmed in tank 1^a, which may be heated or warmed by the hot combustion 110 gases from stack 58^a. These hot combustion gases travel in the path indicated by the arrows and the water in the relatively shallow trough travels in the opposite direction. In the tank there are a series of 115 baffles which prevent the water in the cooler compartment from mixing with the water in the warmer compartment (each compartment being separated from the next by a baffle), although of course, the water flows from the cooler compartment, to the warmer compartment, in such measure as determined by the quantity of water that is withdrawn through pipes 11^a and 92. Water enters the tank 1^a at the end opposite the pipes 120 11^a

and 92, and the inlet may be controlled by a float-feed device, (not shown), if the household is equipped with running water or, if on a farm where usually no running water is provided, water may be poured in as convenient or necessary. Compartment 95 of the tank is the warmest; compartments 96 and 97 are intermediate, and compartment 98 is the coldest. The baffles between the several compartments are indicated at 99 and 100. Suitable insulating covers 101 and 102, may be employed with the water heating tank.

The heat contained in the combustion gases, which would otherwise be lost, may be utilized to heat this tank, and if at any time hot water is desired when the retort is not in full action and generating gas, or if a larger amount of extra hot water is wanted, then the opening 105 under the tank may be utilized. This opening is provided with a cap or cover 106, which may be swung down, and after a burner 107 is turned on and the gas ignited, this burner, which may be pivotally hung at 107^a, may be swung up into place within said opening 105, just below the tank, so that the water therein may become quickly heated to the desired temperature.

30 The structure shown in Fig. 3, constituting a further modification of my invention, includes the same elements specified as being common to the several modifications all as more fully described hereinafter.

35 In the drawings, 1^b and 1^c designate, respectively, reservoirs for water and liquid fuel; such liquid fuel being fuel oil, crude oil, crude oil residuum, tar, pitch, asphalt, or the like. Valves 110 and 111 are arranged 40 in a pipe line 112 which supplies air pressure from a suitable source upon the water and fuel; the valves being arranged to regulate and maintain a constant pressure. The amount of pressure required will vary; in 45 some instances being relatively slight and depending, in some measure at least, upon the size and capacity of the apparatus. A heating and generating chamber is provided by the retort wall 113, having a door 114, leading to a burner compartment 115, and by opening this door 114, a gasoline torch or the like may be inserted to start the apparatus. For the purpose of supplying fuel for the operation of the apparatus, an 50 auxiliary tank 116, receiving liquid fuel from the main reservoir 1^c, via a pipe 117, valved at 118, is provided, in which the liquid fuel may be maintained at a constant level by a float 119.

55 Pipes 120 and 121, having stop valves 122 and 123, connect the compressed air pipe 112, with the main water and liquid fuel reservoirs 1^b and 1^c, respectively. Similarly a pipe 124, valved at 125, connects the main water reservoir 1^b with an auxiliary water tanks or reservoirs for holding a supply of

reservoir 126. Water may be delivered from this reservoir 126, through a pipe 127, by air pressure from pipe 112, entering said reservoir via a pipe 127^a having a stop valve 128; the water so delivered being discharged from a port 129, into a heating and vaporizing pipe 130, forming a chamber 131, and located within the heating casing 113. Pipes 132, and 133, the former leading from pipe 112 to supply the necessary air pressure and having a stop valve 134, also connect the auxiliary fuel tank with the pipe 130 providing the vaporizing chamber 131; the pipe 133 discharging therein through a port 135. The liquids in the auxiliary reservoirs or tanks 116 and 126 are kept at a constant level by floats 119 and 136, respectively, so that the amount of liquid fed into vaporizing pipe 130 therefrom increases when the pressure drops in this vaporizing pipe; the air pressure supplied being constant.

The vaporizing pipe 130 is maintained in a highly heated condition by a heating system; the arrangement, operation and regulation of which will be later described, and the water passing into vaporizing pipe 130 through port 129 from pipe 127 is evaporated and in the form of superheated steam moves past the inlet port 135 of pipe 133. The fuel passing into the hot vaporizing pipe 130 through port 135 meets the superheated steam and is more or less completely vaporized; a condition depending upon the nature of the liquid fuel and the temperatures obtaining.

100 Dependent upon the temperature, the fuel and steam vapors react chemically more or less with one another and form a gaseous mixture which passes a tee connection 137, thence through a pipe 138 and enters the end 105 of a pipe 139. The mixture, now in the form of a fixed gas, passes out of the vaporizing and reaction chamber 131 through pipes 139 and 140; the former lying within the pipe 130 and connected in axial alignment with the tee connection 137. The mixture continues on its way through pipe 140 into a cooler and separator 141, and through pipe 142 to a scrubber 143; which elements are preferably set in close proximity to the main and auxiliary reservoirs or tanks 1^c and 116, containing the liquid fuel, in order to keep the same warm and quite fluid.

110 Some of the heat contained in the gaseous mixture may be utilized to heat the water 120 in the auxiliary reservoir 126, by passing it through a jacket or casing 144 surrounding said reservoir, via a valved connection 145 (as indicated by dotted lines, Fig. 3). Any vapors that may condense in the separator 141 or in the scrubber 143, may be withdrawn through pipes 146 and 149, suitably valved at 150 and 151, respectively. The separator and scrubber may also serve as 115 125 water tanks or reservoirs for holding a supply of

gas under pressure, by providing the inlet pipe 140 leading to the cooler and separator 141, and an outlet pipe 152 leading from the scrubber 143, with stop valves 153 and 154, respectively.

From the scrubber 143, the gaseous mixture may be passed through pipe 152, stop valve 154, and a pipe 155, into a regulating apparatus, some of it going to a burner 156 and the remainder being available for external consumption. The gaseous mixture for external use may pass through a pipe 157 and an adjustable valve 158 to a pipe 159 having a reducing valve 160, whereby the pressure of the gas is reduced to a substantially constant amount; thence passing to a storage or delivery tank 161. Between the two valves 158 and 160 there may be tapped off from the pipe 159 a small pipe 162, which 20 communicates with a special regulator 163. By means of this regulator, a valve 164 located in the pipe 159^a may be gradually, but never completely, closed whenever it is attempted to withdraw from the generator 25 more gas than it should deliver for external consumption; thereby insuring the passage of sufficient gas to the burner 156 at all times.

Another regulator valve 165 maintains the pressure in pipe 159^a, just beyond this valve and between valves 164 and 165 substantially constant. Between the valves 160 and 165, I place a special regulator valve 167, which may be actuated by a diaphragm 35 pressure regulator 168. The space above the diaphragm in the pressure regulator 168, communicates through a small pipe 169 with the storage or delivery tank 161. When the consumption of gas increases, the pressure in the delivery tank is communicated to the space above the diaphragm of the pressure regulator 168, and the valve 167 automatically opens to a greater extent. In this way 40 more gas is allowed to pass for external consumption; always subject, however, to certain limitations so as to insure against too much being taken which, as already explained, is prevented by the controlling valve 164. After leaving this valve, the 45 gas passes through an adjustable valve 170 into tank 161, and through another adjustable valve 171, to a reducing valve 172, which reduces it to substantially constant pressure for consumption; passing finally through a 50 delivery controlling valve 173.

Any gas employed for consumption by the burner 156 to heat the generator, may be conveyed by a pipe 174 branching off from pipe 157 through a reducing valve 175, thus 55 reducing the pressure to a substantially constant one in the pipe 174. From pipe 174 there is taken a constant supply of gas through a pipe 176, adjusting valve 178, pipe 179, and stop valve 180, to the burner 156; 60 being joined in said pipe 179 by gas flowing

through a pipe 181. The burner 156 may also be supplied with a varying amount of gas through said pipe 181; such gas passing a regulator valve 182. This regulator valve 182 maintains the pressure substantially constant in a pipe 183, disposed in line and in communication with pipe 174, that is to say, it prevents it from dropping below a certain point. Between the two regulator valves 175 and 182, a special regulator valve 184, and stop valve 185 are located in the pipe 183. While my present apparatus will operate without the use of the two pressure-maintenance valves 164 and 182, I prefer to 70 use them.

The valve 184 is operated in a simultaneous or interlocking manner with the special regulator valve 167, so that the opening and closing of these two valves occurs substantially at the same time, and so that the intermediate positions of the two valves are in a special and fixed regulation to one another. In other words the burner 156, 75 may be supplied first with a fixed amount of gas and then with an additional amount of gas, dependent upon the amount of gas taken from the generator and substantially proportioned to the amount of material (water and liquid fuel) fed to the generator. Between the regulator valves 182 and 184, 80 the stop or controlling valve 185 is placed.

When necessary or desirable, such liquid fuel or the residuum therefrom as may not have been vaporized by the time it reaches the tee connection 137, may be withdrawn therefrom through an apertured plug 186, and pipe 187, and passed to a tank 189. The tank 189 may contain means, such as a float 190, controlling the outlet so that liquid products therein may be automatically withdrawn through a pipe 191, valved at 192, or they may be passed through a pipe 193 having an adjustable valve 194, and stop valve 195; to the burner 156. These liquids are substantially proportional to the amount of liquids fed to the generator, and they 95 therefore fluctuate in amount.

The hot combustion gases from burner 156 pass upward into the chamber formed by the retort wall 113 of the generator and first heat a cap 196, and pipe 138. Then the hot combustion gases travel past tee 137, and at the point 197 they should be joined by waste heat and hot gases, if such are available; the hot gases from an engine exhaust 198, for instance, if the gas developed by the generator should be employed to run a gas engine. The products of combustion, waste gases, pass on their way, heating pipe 130 and may be discharged through an outlet 200.

In addition to and in some cases in lieu of employing a valve of the character illustrated at 52, in Fig. 1, to control the supply of gas to the main burner, I may employ 100

a throttle valve 201, having an operating lever 202, to which is connected an operating cord 203, which passes over a guide pulley 204, and is connected at 205, to the end of 5 a lever 206, pivoted at 207, all as shown by dotted lines in Fig. 1. The lever 206 carries a weight 208 so as to lie normally in the position indicated in the drawing, with the end of the lever in position to be engaged by the lug 600 so as to be moved when the bell rises.

This throttle valve 201 is open when the bell starts to rise and is gradually closed as the gas tank or shell fills with gas. When 15 I use the throttle valve 201, I prefer to operate the governed valve 72^b in the pipe line 73 supplying gas to the intermediate burner 49, in such a manner that the gas is turned on as described but that it is not turned off 20 until the bell reaches the upper limit of its travel.

In the form of apparatus shown in Fig. 1, I have illustrated the use of a meter 210, or similar device, indicated by dotted lines 25 and also shown in Fig. 5, which may serve as a motor. The inlet 211 and outlet 212 of this meter, in communication with the pipe 53 are shown directly adjacent a valve 213 in said line, and said inlet and outlet are 30 provided with valves 211^a and 212^a, respectively. By means of suitable gearing, indicated at 214, the action of the meter is transmitted to a suitable pump, diagrammatically indicated at 215, and designed to pump oil 35 from a feed pipe 216, or other source and deliver the same to the feed line for passage through the valve 6, and thence to the retort in lieu of delivery from the tank 1 via pipe 5. The amount of oil delivered by the pump 215 is in direct proportion to the amount of gas delivered for consumption by the main burner.

The result of this throttle control is such that at various intermediate loads, the retort will generate gas at capacities about as in the apparatus illustrated in Fig. 3. Dependent, however, on the relative cubical measurements of the bell 30, (Fig. 1), and of the delivery tank 161, (Fig. 3), respectively, 50 there will be more or less lag; but essentially the effect of these two methods of governing may be identical at intermediate loads. However, it is also clear that a pump, the fuel-feed in the form of apparatus illustrated in Fig. 1, is more positive, and that the thermal efficiency at low loads, is greater in the form of apparatus shown in Fig. 1.

In connection with the structure shown in Fig. 3, a pressure-distributing system may be used as a substitute for the delivery-tank 161 as part of the regulator; individual house-governors taking the place of the valve 172 shown in Fig. 3, in the main gas line, 60 which valve 172 reduces the gas flow to substantially constant pressure. The varying

pressure in the pressure-distributing system, of course, would serve the same purpose as the varying pressure in the delivery-tank 161 in that it would vary the opening of the two valves 167 and 184; the actuating members of which are shown as being linked together.

I claim:

1. In apparatus for producing a fixed gas, the combination of a heating chamber from 75 which the air is excluded, means for feeding liquid fuel thereto under pressure, means for maintaining an approximately constant temperature in said chamber for vaporizing and gasifying said liquid fuel 80 therein, means for increasing the temperature of said chamber in accordance with the amount of fuel treated, and means for withdrawing unvaporized fuel products from said heating chamber which have not been 85 vaporized and utilizing the same to produce additional heat.

2. In self-governing apparatus for producing a fixed gas, the combination of a gasifying chamber from which air is excluded, 90 means for feeding liquid fuel thereto under pressure, means for maintaining a high temperature in said chamber and gasifying the liquid fuel fed thereto, automatic means for varying the amount of heat supplied to said chamber in accordance with the amount of fuel treated, means for collecting and cooling the gas thus formed, and means for withdrawing ungasified fuel products from 95 said gasifying chamber and utilizing these 100 products to produce additional heat.

3. In apparatus for treating liquid fuel for the production of a fixed gas, a source of liquid fuel, means for subjecting such liquid fuel to pressure whereby it is caused to flow to a heated space or zone from 105 which the air is excluded, means for heating such space to effect vaporization of the fuel, means for withdrawing from such heated zone the unvaporized products, means for subjecting the gaseous vapors to additional heating, and means for cooling and collecting the gas thus formed.

4. In apparatus for treating liquid fuel for the production of a fixed gas, a source of liquid fuel, means for subjecting such liquid fuel to pressure whereby it is caused to flow to a heated space or zone from which the air is excluded, means for heating such zone to effect vaporization of the fuel, means for withdrawing from such heated zone the unvaporized products, means for subjecting the gaseous vapors to additional heating, means for cooling and collecting the gas thus formed, and means for simultaneously and proportionally varying the liquid fuel feed and the additional heating.

5. In apparatus for treating liquid fuel 130 for the production of a fixed gas, a source

- of liquid fuel, means for subjecting such liquid fuel to pressure whereby it is caused to flow to a heated space or zone from which the air is excluded, means for heating such zone to effect vaporization of the fuel, means for withdrawing from such heated zone the unvaporized products, means for subjecting the gaseous vapors to further heating, means for cooling and collecting the gas thus formed, and means whereby the various regulating elements are simultaneously actuated or operated to regulate production in accordance with the demand.
6. In apparatus for treating water and liquid fuel for the production of a fixed gas, the combination of means for subjecting said water and liquid fuel to pressure whereby it is caused to flow to a heated space or zone from which the air is excluded, means for heating such zone to effect vaporization of the water and fuel, means for withdrawing from such heated zone the unvaporized products, means for subjecting the gaseous vapors to further heating, means for varying the heat supplied in accordance with the amount of liquids fed, and means for cooling and collecting the gas thus formed.
7. In self-governing apparatus for treating water and liquid fuel for the production of a fixed gas, the combination of heating means, means for subjecting said water and liquid fuel to pressure whereby it is caused to flow to the heated space or zone from which the air is excluded, means for heating such zone to effect vaporization of the water and fuel mixture, means for withdrawing from such heated zone the unvaporized products, means for subjecting the gaseous vapors to further heating, means for cooling and collecting the gas thus formed, and means simultaneously actuated or operated to regulate production in accordance with the demand.
8. In apparatus for producing a fixed gas, the combination of a heating chamber, means for heating the same, a vaporizing chamber from which air is excluded; said vaporizing chamber having passages providing for the flow of gaseous vapor in more than one direction, means for introducing water under pressure to said vaporizing chamber wherein it is evaporated to steam, means for introducing liquid fuel to said vaporizing chamber under air pressure whereby such steam may commingle therewith; said heating operation continuing until a complete mixture of the steam and vaporized fuel has taken place, means for further heating the vaporous body whereby a fixed gas is produced, means for finally cooling and collecting the gas, and means for withdrawing unvaporized products from the heated zone.
9. In apparatus for producing gas, the combination of a heating chamber, means for heating the same, a vaporizing chamber from which the air is excluded, said vaporizing chamber having passages providing for the flow of gaseous vapor in a plurality of directions, means for introducing water under pressure to said vaporizing chamber wherein it is evaporated to steam, means for introducing liquid fuel to said chamber under pressure whereby the steam generated may commingle therewith, means for further heating the vaporous body, means for removing the unvaporized products from said vaporizing chamber and utilizing said products as fuel, means for finally cooling and collecting the gas, and means whereby the various regulating elements are simultaneously actuated or operated to regulate production in accordance with the demand.

In witness whereof I have signed this specification.

BENJAMIN F. BROOKE SEWELL.
